CLAIM

The ornamental design for an integrated MIMO and SAR radar antenna, as shown and described.

DESCRIPTION

FIG. 1 is a perspective view of a top plate of an integrated MIMO and SAR radar antenna;

FIG. 2 is a top view thereof;

FIG. 3 is an enlarged and isolated portion of FIG. 2, showing broken lines to indicate the interior portion forms no part of the claimed design; and

FIG. 4 is an enlarged and isolated portion of FIG. 2, showing broken lines to indicate the interior portion forms no part of the claimed design.

FIG. 5 is a top view thereof;

FIG. 6 is a bottom view thereof;

FIG. 7 is a top view of an offset array of an integrated MIMO and SAR radar antenna; and,

FIG. 8 is a bottom view of an offset array.

The broken lines illustrate portions of the article that form no part of the claimed design.
